No. 36,326.

Patented May 12, 1903.

UNITED STATES PATENT OFFICE.

GEORGE H. ULLMAN, OF NEW YORK, N. Y.

DESIGN FOR A CHANDELIER.

SPECIFICATION forming part of Design No. 36,326, dated May 12, 1903.

Application filed January 6, 1903. Serial No. 138,074. Term of patent 3½ years.

To all whom it may concern:

Be it known that I, GEORGE H. ULLMAN, a citizen of the United States, residing in the borough of Manhattan, city of New York, State of New York, have invented and produced a new, original, and ornamental Design for Chandeliers, of which the following is a description.

My new design is illustrated in the accompanying drawing, forming part hereof; and it consists of the main body, composed of a cylindrical portion 1, the ornamental pendant 2 of urn-like form, from which depends a conventionalized lotus-bud, the bowl of the urn-like part being ornamented with an ovoid border, the ornamental crown 3, the main portion of which is surrounded by a row of pearls and from which rises the eye 4, en-

gaged by a ring 5, connected with the canopy or bell 6, the arms 7 extending out from the body and having the enlarged foliated portion 8 and upwardly-extending forward portions 9, from which depend the globe-holding canopies 10, supporting spherical globes.

Having now described my invention, what I claim as new, and desire to secure by Letters Patent, is—

The ornamental design for a chandelier herein shown and described.

This specification signed and witnessed this 3d day of January, 1903.

GEORGE H. ULLMAN.
